UNITED STATES PATENT OFFICE.

STANLEY L. FISHER, OF CHESTER, CONNECTICUT, ASSIGNOR TO PRATT READ PLAYER ACTION COMPANY, OF DEEP RIVER, CONNECTICUT.

AUTOMATIC MUSICAL INSTRUMENT.

Application filed September 30, 1922. Serial No. 591,579.

While, as illustrated in the accompanying drawings, my invention is embodied in a device designed to vary the degree of air tension in the vacuum system of a player piano or other musical instrument operated by means of a vacuum pump, it will be apparent that in some of its aspects it is not limited to this type of device, but is equally applicable to pressure operated instruments 10 as well.

My invention more particularly relates to a device for varying the air tension in the vacuum system of a musical instrument by means of the admission thereto, in varying 15 quantities, of atmospheric air and preferably my device is designed to be controlled from the note sheet so as to render the instrument entirely automatic or of the so-called reproducing type. It may, however, 20 be manually operated, if desired.

One object of my invention is the provision of a new and improved expression device for controlling the dynamics of the notes sounded by the instrument.

Another object of my invention is to provide a new and improved expression device for varying the air tension produced in the wind chest by the power source.

Another object of my invention is to provide a new and improved expression device for automatic musical instruments in which a number of various degrees of air tension may be secured, so that the instrument will be capable of a wide range of expression.

Another object of my invention is to provide an expression device of this character, which shall be simple in construction, exceedingly efficient and sensitive in operation, and easy of adjustment.

To these and other ends the invention consists in the novel features and combinations of parts to be hereinafter described and claimed.

In the accompanying drawings:

Fig. 1 is a front elevational view of a player piano provided with my improvements, some of the parts of the instrument case being broken away to show the application of a preferred embodiment of the expression mechanism.

Fig. 2 is a rear elevational view of the expression device removed from the instrument.

Fig. 3 is a sectional view on line 3—3 of Fig. 2;

Fig. 4 is a sectional view on line 4—4 of Fig. 3;

Fig. 5 is a sectional view taken on the broken line 5—5 of Fig. 4;

Fig. 6 is a sectional view on line 6—6 of Fig. 4;

Fig. 7 is a diagonal sectional view on line 7—7 of Fig. 5;

Fig. 8 is a diagrammatic sectional view similar to Fig. 4 but showing diagrammatically the operation of my improved expression device.

The piano shown in Fig. 1 consists of the usual case 10 provided with a roll box 11, take-up and music spools 12 and 13, and a 70 tracker bar 14. Within the case is the usual player action chest (not shown) from which the air is exhausted by means of a duct or tube 15, which leads to an exhausting device 16 of any preferred form.

In order to admit atmospheric air into the vacuum system to modify the action of the air pump or exhaust device, I have shown the duct 15 leading into a vacuum chest 17 to which my expression device 18 is secured. 80 A duct 15^a connects the chest 17 with the exhausting device 16.

As shown in Fig. 3, the chest 17 is provided with a port 19, which registers with a port 20 at the rear side of the box or chest 18 of the expression device, the expression device serving to admit varying quantities of atmospheric air to the vacuum chest through the port 19 to control the degree of exhaust created by the pump.

The chest 18 is provided at its lower portion with a chamber 21 containing atmospheric air at all times, the air passing into the chamber through openings 22. These openings are, in the form shown, covered by strips of felt or the like 23 to muffle the sound of the air passing into the chest. While provision may be made for as many different degrees of expression as it is desired to have, in the illustrated embodiment of my invention I have arranged for five different degrees of air tension in the action chest and to this end I have provided four valve ports through which the air is adapted to enter and pass into the vacuum chest 17. It will be understood that one degree of air tension obtains when all of the ports are open and a different degree for each one of the ports that is closed. These four ports are at the lower open ends of the chambers 100 105 110

24, 25, 26 and 27 and their effective areas may be varied by the valves 28, 29, 30 and 31 mounted upon the stems 32, 33, 34 and 35 by which they may be regulated to vary the effective opening of the respective ports and thereby vary the amount of atmospheric air admitted to the vacuum system.

Each of the four chambers communicates with the adjacent one in such a manner that 10 air in passing from one to the other must pass below a diaphragm or pouch pneumatic by which the communication between the chambers may be controlled. It may also be stated at this time that the air in passing 15 from certain of these chambers to the vacuum system must pass through the remaining chambers which lie between that chamber and the port 20. In other words, air passing into the chamber 27 by the valve 31 20 must pass through the chambers 26, 25 and 24 successively to reach the vacuum system. In like manner air entering the chamber 26 must pass through the chambers 25 and 24 and air entering the chamber 25 must pass 25 through the chamber 24 before entering the vacuum system. It will be seen, therefore, that when one of these chambers is cut off from communication with the vacuum system, the remaining chambers beyond the one 30 under consideration will also be cut off.

In effecting such an arrangement, each of these chambers opens at its upper end into one of the pouch chambers 36, 37, 38 and 39, and also communicating with each of these 35 pouch chambers is one of the annular recesses 40, 41, 42 and 43. Diaphragms 44, 45, 46 and 47 are arranged in the respective pouch chambers and each is adapted to cover one of the chambers 24, 25, 26 and 27 and 40 also the corresponding recess. Communicating with each of the chambers 24, 25 and 26 is one of the passages 48, 49 and 50 and to establish communication between these passages and the adjacent chambers are the 45 bores 51, 52, 53, 54, 55 and 56 arranged in pairs as shown in Fig. 5, each pair communicating at one end with one of the annular recesses and at the other end with one of the passages 48, 49 or 50.

To control the admission of air through the ports regulated by the valves 28, 29, 30 and 31, a series of valves is arranged at the upper portion of the chest 18 to control the admission of atmospheric air or exhaust in 55 the pouch chambers 36, 37, 38 and 39 above the pouches or diaphragms therein. These valves 58, 59, 60 and 61 are of the usual primary type and are mounted in pouch chambers 62, 63, 64 and 65, which contain the pouches 66, 67, 68 and 69 to control the valves in the usual manner. A duct 70 leads from each of the valves to the respective pouch chamber above the diaphragms 44, 45, 46, and 47 and provision is made for 60 admitting air to the pouch chambers below 65

these valves from the note sheet by means of the ducts 71, 72, 73 and 74, which lead to openings in the tracker bar. The pouch chambers above the pouches 66, 67, 68 and 69 are kept in an exhausted condition by 70 means of passages 75 and 76, which lead from the pouch chamber above the diaphragm 66 to the passage 77, which communicates with the chest 17 through the ports 19 and 20, and by means of the passages 78, 79 and 80, which connect the four pouch chambers above the respective pouches. The pouch chambers below these pouches are normally kept in an exhausted condition by means of the bleed openings 81. 80

In the operation of my device, it will be apparent that air entering the chamber 27 will pass up below the diaphragm 47 into the annular recess 43, downwardly through the bores 56 and 55 into the passage 50, 85 thence into the chamber 26 where, together with the air entering past the valve 30, it will pass upwardly below the diaphragm 46 into the annular recess 42, through the bores 53 and 54 into the passage 49, thence into 90 the chamber 25, below the diaphragm 45 into the annular recess 41, downwardly through the bores 51 and 52 into the passage 48, thence into the chamber 24, below the diaphragm 44 into the annular recess 40, 95 thence into the passage 77 through the ports 19 and 20 into the vacuum system by way of the chest 17. The valves 28, 29, 30 and 31 may be regulated to vary the effective opening of the ports which they control so 100 as to control the admission of air through these ports to the wind chest.

In its normal condition, that is when the diaphragms 44, 45, 46 and 47 are in the position shown in Fig. 4, as they are when 105 there are no openings in the note sheet to admit air to the ducts 71, 72, 73 and 74, atmospheric air will be admitted to the wind chest through all of the four valve control ports and the instrument will be sounding 110 its notes of lowest intensity or pianissimo. If it is desired to raise the degree of air tension in the wind chest one step for piano effect for instance, an opening is cut in the note sheet to admit air to the tracker duct 115 74, which will cause the valve 61 to be raised and allow atmospheric air to pass into the pouch chamber above the diaphragm 47 through the passage 70. As a partial vacuum exists below this diaphragm, the latter will 120 be forced downwardly to cover the recess 43 and the passage of air into this recess from the channel 27 will no longer be permitted. It will be apparent that under these conditions the only air permitted to enter the vacuum system will be that passing about the valves 28, 29 and 30 and the degree of exhaust obtained by the pump will be raised. If, on the other hand, a still louder tone is 125 desired, such for instance as mezzo forte, an 130

opening is cut in the note sheet to admit air to the tracker duct 73, which will cause the valve 60 to admit air above the diaphragm 46 and thus both of the ports controlled by the valves 30 and 31 will be cut off from the vacuum system, so that no air will be permitted to enter the latter through these ports. In the same manner forte and fortissimo effects may be produced by the admission of atmospheric air into the tracker ducts 72 and 71, respectively, thus forcing the pouches 45 and 44 downwardly to close the recesses 41 and 40. When the recess 41 is closed by the diaphragm 45, the only air which can enter the vacuum system will be that passing about the valve 28, while when the recess 40 is closed by the diaphragm 44, it will be apparent that the instrument will be playing its loudest tones, as no air will be admitted to the vacuum system. Variations in the effect produced by the admission of air to the various tracker ducts may be secured by regulation of the regulating valves 28, 29, 30 and 31 to vary the effective openings of the inlet ports and likewise, as has been stated before, if a greater variety of degrees of air tension is desired, the number of inlet ports may be increased.

It will also be obvious that when it is desired to sound the instrument with any particular degree of loudness whether fortissimo or piano, it is only necessary to provide one opening in the note sheet, as the closing of any one of the diaphragm valves cuts off all of the inlet ports beyond this valve.

In Fig. 8 of the drawings, I have shown, in a diagrammatic form, the operation of my expression device. In this case the wind chest is shown diagrammatically at 101, the exhauster at 102 and leading into the duct 103 through which the air is drawn from the wind chest is the duct 104 which communicates with the expression device. The regulating valves 105 control the inlet of atmospheric air into the chambers 106 from which this air passes below the diaphragms 107 into the ducts 108, whence it is carried through the adjacent chamber 106 and below its diaphragm 107 until it reaches the vacuum system through the duct 103. Through the note sheet openings atmospheric air is admitted into the inlet ports 109, below the diaphragms 110, which causes the valves 111 to be raised to admit air through the ducts 112 above the pouches 107 to cause the inflation of these pouches to cover the ducts 108. The operation is similar to that which takes place in the expression device shown in the remaining figures of the drawing, but is in somewhat simpler form to show in a diagrammatic way the course of the air through the inlet ports to the vacuum system.

It will be understood that while the effective area of the atmosphere ports at the

lower ends of the chambers 24, 25, 26 and 27 may be varied by regulation of the valves 28, 29, 30 and 31, the admission of air to the vacuum system through these ports is positively controlled by the diaphragms 44, 45, 70 46 and 47 which act as valves in closing the upper ends of these chambers but closing the communication between them and the recesses 40, 41, 42 and 43, and thus cut off communication between the chambers and 75 the vacuum chest 17. In fact these diaphragms may be provided with valves to seat upon these chambers, if desired, but it has been determined that such a provision is not necessary as the diaphragms alone are effective to prevent the admission of air to the vacuum chest through these chambers.

While I have shown and described a preferred embodiment of my invention, it will be obvious that the same is not to be limited 85 to all of the details shown, but is capable of many modifications and variations within the spirit of the invention and within the scope of the appended claims.

What I claim is:

1. In an expression device for musical instruments including a vacuum system having an air inlet, means to control the admission of air through said inlet including a plurality of constantly open atmosphere ports, 95 and means for preventing the admission of atmospheric air through each of said ports, the means associated with one port also preventing the admission of air through another port. 100

2. An expression device for musical instruments, having a vacuum system provided with an air inlet, comprising means to control the admission of air through said inlet including a plurality of constantly open atmosphere ports, an independently operable means for controlling the admission of atmospheric air through each of said ports, the means associated with one port also controlling the admission of air through an adjacent port. 105 110

3. An expression device for musical instruments, having a vacuum system provided with an air inlet, comprising means to control the admission of air through said inlet 115 including a plurality of constantly open atmosphere ports and individually operable valves for controlling the admission of air to the vacuum system through said ports, the valve associated with one port also controlling the admission of air through another port. 120

4. An expression device for musical instruments, having a vacuum system, comprising means providing a plurality of constantly open inlet ports to admit atmospheric air to said system, individually operable means to control the admission of air to the vacuum system through said ports, the controlling means associated with one port 125 130

also controlling the admission of air through an adjacent port.

5. An expression device for musical instruments, having a vacuum system, comprising means providing a plurality of constantly open inlet ports to admit atmospheric air to said system, and note sheet controlled, individually operable, means to control the admission of air to the vacuum system through said ports, the controlling means associated with one port also controlling the admission of air through an adjacent port.

6. An expression device for musical instruments, having a vacuum system, comprising means providing a plurality of constantly open inlet ports to admit atmospheric air to said system, note sheet controlled means to control the admission of air to the vacuum system through said ports, the controlling means associated with one port also controlling the admission of air through an adjacent port.

7. An expression device for musical instruments, having a vacuum system, comprising means for admitting atmospheric air to said system including a duct leading thereinto, means providing a plurality of constantly open atmospheric inlet ports communicating in series arrangement with said duct, means for cutting off the admission of atmosphere to the duct through each of said ports, the means associated with one of said ports also cutting off the admission of atmospheric air through the ports beyond the said port.

8. An expression device for musical instruments, having a vacuum system, comprising means for admitting atmospheric air to said system comprising a plurality of constantly open ports, valves for controlling the admission of air through said ports, and means whereby the air entering one of said ports must pass by the valve of an adjacent port to enter the vacuum system.

9. An expression device for musical instruments, having a vacuum system, comprising means for admitting atmospheric air to said system, said means including a plurality of valved ports arranged in series whereby the air passing through one of said ports must pass by the associated valve and the valves of the remaining ports of the series, each valved port being provided with an individual atmospheric inlet.

10. An expression device for musical instruments, having a vacuum system, comprising means for admitting atmospheric air to said system, including a plurality of open inlet ports and note sheet controlling means to control the passage of air to the vacuum system from said ports, certain of said controlling means being arranged to control the admission of air through a plurality of said ports, and additional means

for varying the quality of air entering said ports.

11. An expression device for musical instruments, having a vacuum system, comprising means for admitting atmospheric air to said system, said means having a plurality of constantly open ports of different effective capacities and provided with valves to cut off the admission of air to the chest through said ports, and means whereby the valve associated with one port also prevents the admission of air through the ports of greater effective capacity.

12. In an automatic musical instrument, a vacuum system having a plurality of constantly open atmospheric ports through which air may be admitted thereto, a valve to control the admission of air through each of said ports, and means for controlling the air entering one of said ports by the valve associated with an adjacent port.

13. In an automatic musical instrument, a vacuum system having a plurality of constantly open atmospheric ports through which air may be admitted thereto, a valve to control each of said ports, and means whereby the air entering one of said ports must pass by the valves of the ports between that port and the vacuum system and be controlled thereby.

14. In an automatic musical instrument, a vacuum system, means for varying the degree of exhaust in said system, comprising a plurality of chambers adapted to be placed in communication therewith, valved means for controlling communication between said chambers and the vacuum system, and a constantly open individual atmospheric inlet port for each of said chambers.

15. In an automatic musical instrument, a vacuum system, an expression device having a passage communicating with said system, a plurality of chambers in said device, means for admitting atmospheric air at all times to each of said chambers individually, means providing communication between said chambers, and means providing for communication between one of said chambers and the passage leading to the vacuum system.

16. In an automatic musical instrument, a vacuum system, an expression device having a passage communicating with said system, a plurality of chambers in said device, means for admitting atmospheric air at all times to each of said chambers individually, valve means providing communication between said chambers, and means providing for communication between one of said chambers and the passage leading to the vacuum system.

17. In an automatic musical instrument, a vacuum system, an expression device having a passage communicating with said system, a plurality of chambers in said device,

regulable means for admitting atmospheric air at all times to each of said chambers individually, means providing communication between said chambers, and means providing 5 for communication between one of said chambers and the passage leading to the vacuum system.

18. In an automatic musical instrument, a vacuum system, an expression device having 10 a passage communicating with said system, a plurality of chambers in said device, means for admitting atmospheric air at all times to each of said chambers individually, comprising ports controlled by regulable 15 valves, means providing communication between said chambers, and means providing for communication between one of said chambers and the passage leading to the vacuum system.

20 19. In an automatic musical instrument, a vacuum system, having an atmospheric air inlet port, a plurality of chambers arranged in series, one of which is in communication with said inlet port, means to admit atmospheric air at all times to each of said chambers individually, and means to cut off the 25 admission of air to the vacuum system from a part of the series.

20 20. In an automatic musical instrument, a vacuum system having an inlet port, an expression device having a plurality of chambers, one of which is in communication with said port, said chambers being open to the atmosphere at one end thereof, means providing communication between said chambers, and pneumatically operated means to close the opposite ends of said chambers to control the communication between said chambers.

40 21. In an automatic musical instrument, a vacuum system having an inlet port, an expression device having a plurality of chambers, one of which is in communication with said port, said chambers being open to the atmosphere at one end thereof, means providing communication between said chambers, and pneumatically operated means to close the opposite ends of said chambers, note sheet controlled pneumatically operated 45 means to control the communication between said chambers.

55 22. In an automatic musical instrument, a vacuum system having an inlet port, an expression device having a plurality of chambers, one of which is in communication with said port, said chambers being open to the atmosphere at one end thereof, means providing communication between said chambers, and pneumatically operated means to 60 close the opposite ends of said chambers to control the communication between said chambers, and means to control the communication between said one chamber and said inlet to the vacuum system.

65 23. In an automatic musical instrument, a

vacuum system having an inlet port, an expression device having a plurality of chambers, one of which is in communication with said port, said chambers being open to the atmosphere at one end thereof, means providing communication between said chambers, pneumatically operated means to close the opposite ends of said chambers to control the communication between said chambers, and pneumatically operated means to 70 control the communication between said one chamber and said inlet to the vacuum system.

24. In an automatic musical instrument, a vacuum system having an inlet port, an expression device having a plurality of chambers, one of which is in communication with said port, atmospheric ports arranged at one end of each of said chambers, means providing communication between said chambers, and pneumatically operated means at 75 the opposite ends of said chambers from said atmospheric ports to control the communication between said chambers, and note sheet controlled pneumatically operated means to control the communication between 80 said one chamber and said inlet to the vacuum system.

25. In an expression device for a musical instrument, having an exhaust system, 85 means for admitting atmospheric air to said system comprising a chest, a plurality of open ended chambers arranged side by side therein, each of said chambers communicating with the atmosphere through one end thereof, means providing communication between the other end of certain of said chambers and an adjacent one of said chambers, means for closing the last named end of each of said open-ended chambers to cut off the communication with the adjacent chambers, and means for placing one of said chambers in communication with the vacuum 90 system.

26. In an expression device, an expression 100 chest, a plurality of chambers extending into said chest from one face thereof and being open to the atmosphere at their outer ends, means for regulating the admission of atmospheric air through said chamber ends, means for establishing communication between the inner ends of each of said chambers and an adjacent one of said chambers, means for closing the said inner ends of the chambers to cut off said communication, and means for providing communication between one of said chambers and the vacuum system of a musical instrument.

27. In an expression device, an expression 110 chest, a plurality of chambers extending into said chest from one face thereof and being open to the atmosphere at their outer ends, 115 passages leading from each of said chambers to a point adjacent the inner end of an adjacent chamber, means for controlling 120 communication between the inner ends of 125

130

the chambers and said passages, and means providing communication between one of said chambers and the vacuum system of a musical instrument.

5. 28. In an expression device, an expression chest, a plurality of chambers extending into said chest from one face thereof and being open to the atmosphere at their outer ends, an annular recess surrounding the inner ends
10 of each of said chambers and adapted to communicate therewith, a passage leading

from each of said recesses to an adjacent chamber, a diaphragm covering the inner end of each of said chambers to cut off communication between it and the annular recess, and means providing communication between one of said chambers and the vacuum system of a musical instrument. 15

In witness whereof, I have hereunto set my hand this 27th day of September, 1922.

STANLEY L. FISHER.

Certificate of Correction.

It is hereby certified that in Letters Patent No. 1,591,300, granted July 6, 1926, upon the application of Stanley L. Fisher, of Chester, Connecticut, for an improvement in "Automatic Musical Instruments," errors appear in the printed specification requiring correction as follows: Page 1, line 1, before the word "While" insert the paragraph—

My invention relates to automatic musical instruments and more especially to an expression device for use in connection with such instruments; page 4, line 66, claim 10, for the word "quality" read quantity; and that the said Letters Patent should be read with these corrections therein that the same may conform to the record of the case in the Patent Office.

Signed and sealed this 3d day of August, A. D. 1926.

[SEAL.]

M. J. MOORE,
Acting Commissioner of Patents.
